ELECTRICAL MUSICAL INSTRUMENT

Nicholas Langer, Deep River, Conn., assignor of
sixty-six and two-thirds per cent to John Hal-
mágyi, Budapest, Hungary

Application April 5, 1933, Serial No. 664,486

10 Claims. (Cl. 84—1)

The present invention relates to electrical musical instruments containing glow-discharge lamps and more particularly to electrical musical instruments of the type using glow-discharge lamp circuits to produce electric oscillations of different frequencies capable of being transformed into musical sounds of different pitch.

It is an object of the present invention to provide an electrical musical instrument having a better control of the frequency and of the wave form of the electrical oscillations produced by the charging and discharging of condensers through resistances and glow-discharge lamps.

It is a further object of the invention to provide an electrical musical instrument capable of extending the pitch range thereof by collectively changing the frequencies of a plurality of musical notes while at the same time maintaining their relative frequencies or intervals unchanged.

It is another object of the invention to provide an improved method for producing small periodic changes in the pitch of the musical notes, called the "tremolo effect", and to use the same means for obtaining a good imitation of the sound quality characteristic to the tone of a mandolin or banjo or generally to that of the plucked string.

It is also within the contemplation of the present invention to provide an improved and simple circuit for producing a multiplicity of electrical oscillations of different frequencies capable of individual adjustment.

Other and further objects of the invention will become apparent from the following specification taken in conjunction with the accompanying drawings in which

Fig. 1 is a diagrammatic view of a glow-discharge lamp oscillator containing a variable series impedance in the main circuit embodying the principles of the present invention;

Fig. 2 shows a schematic view of a circuit of an electrical musical instrument of the glow-discharge lamp type embodying the present invention in which the absolute pitch of every note can be changed simultaneously while at the same time changes in the relative pitches (intervals) are compensated for;

Fig. 3 depicts diagrammatically an improved embodiment of a circuit for producing the so-called tremolo and banjo-effects in an electric musical instrument; and

Figs. 4 and 5 illustrate a schematic view of

a circuit of the improved electric musical instrument using variable condensers for the individual adjustment of a plurality of musical notes.

Broadly stated all of these circuits illustrated and described herein show the fundamental parts which are absolutely necessary in order to obtain the desired effects. Of course, as those skilled in the art will readily understand, a great number of refinements can be applied to each circuit. Most of the electrical elements as capacities, resistances, inductances, and the like can be made variable in steps or continuously as desired. Thermionic amplifiers or transformers can be used between the oscillation generator and the sound-producing means and the output can be taken off in many ways other than connecting the sound-producing means directly in series with the main circuit. Means for changing the amplitude and the harmonic content of the oscillations produced can be provided by potentiometers, filter circuits, etc. in accordance with the conventional practice of the electrical art. Although most of the circuits described are capable of producing one musical note at a time, it is evident that a plurality of musical notes or chords can be produced by arranging a plurality of circuits of similar kind, that certain parts of the circuits such as the source of current and the sound-producing means, may be common to all the circuits.

Referring more particularly to Fig. 1 an arrangement of a glow-discharge lamp oscillator is illustrated. The reference character B designates a current source which is in a circuit containing a glow-discharge lamp G, a resistance R, a condenser C and a sound-producing means L. In the circuit a variable impedance I is connected in series which is preferably an ohmic resistance. By incorporating a variable impedance in the circuit novel and unexpected results of great practical importance can be obtained.

From a theoretical point of view, the frequency of the oscillations produced in a circuit of the aforesaid type is approximately in inverse ratio to the capacity of the condenser and the resistance and the said frequency increases or decreases with the electro-motive force acting in the circuit. Theoretically it would be expected that by connecting an impedance in the circuit, that is by decreasing the electro-motive force in the circuit, the frequency of the oscillations produced would decrease. Con-

trary to expectations and theory, it has been found that if the impedance is increased from zero up to a final value, the frequency will increase with increasing impedance instead of decreasing. As yet, no explanation can be offered for the strange behavior of this circuit but the phenomenon can be easily demonstrated experimentally. It has been also discovered that there must be a certain numerical relation between the value of the capacity of the condenser, of the resistance, of the impedance and of the voltage of the current source B in order to cause the desired effect. For instance, to give a practical example, if the capacity equals 0.001 microfarad, R the resistance equals 1 megohm, the voltage of B about 110 volts, then the impedance can be varied from zero to about 500,000 ohms and the frequency will increase with it, but after passing this critical impedance the glow-discharge lamp will be continuously lighted and will stop oscillating.

In Figs. 2 and 3 circuits are depicted which illustrate practical embodiments of the foregoing principle.

Referring more particularly to Fig. 2 a circuit of an electric musical instrument capable of producing numerous musical notes of different pitch is shown. Reference character B designates the current source, T the output transformer with associated sound-producing means, G is the glow-discharge lamp, C-1 a condenser, I a variable impedance, R-1 to R-n are fixed resistors in series any number of which can be connected across C-1 by operating one of the switching keys K-1 to K-n and closing one of the contacts Q-1 to Q-n. Means for controlling the volume, tone color of the sounds produced or adjusting the electro-motive force; amplifiers and the like auxiliary apparatus have been omitted for the sake of simplicity.

In the practical manufacture of an electrical musical instrument, resistors R-1 to R-n are selected so as to give a different note of the tempered scale for every successive key, K-1 to K-n. Since resistors R-1 to R-n vary between 40,000 and 1,000,000 ohms, no variable resistors of this kind which are inexpensive and constant enough can be obtained on the market. Consequently, it is necessary to have in stock a large quantity of fixed resistors of every intermediary value between said extremes and to select the adequate resistors by a long and tiresome method of trial and error. Although the tuning of an instrument of this kind is remarkably constant, slight variations of the characteristics of the glow-discharge lamp (depending especially on the break-down and extinction voltages) might change the intervals between the individual notes. This can now be easily compensated for all the intervals by the variable impedance I. The effect of increasing the impedance is to make all the intervals closer and vice versa. Thus, the instrument can be tuned for about the middle position of impedance I, that is resistors R-1 to R-n are selected so as to give n successive notes of the tempered scale, when keys K-1 to K-n are actuated. Suppose now that by a change in the characteristics of the glow-discharge lamp the intervals become closer or wider than necessary, they can be easily brought back by adjusting a single control of the impedance. In this manner a tiresome and expensive "retuning" of the instrument (i. e. changing of all the resistors) is

eliminated. A wire-wound or a carbon compression-type resistor capable of variation between zero and 500,000 ohms is preferably used for impedance I.

In Fig. 2, another possible use of the series impedance is also depicted. If a condenser C-2 of approximately the same capacity is connected across C-1, then every note produced by the instrument will sound an octave lower, because the capacity in the circuit is doubled. Musically speaking, the range of the instrument has been "transposed" an octave lower. Of course, by giving suitable values to the condenser C-2, it is possible to transpose the range by any amount, in steps or continuously in case condenser C-2 is continuously variable.

The transposing arrangement is of great practical importance because it extends the range of the instrument considerably. The difficulty of this simple process lies in the circumstance that by connecting condenser C-2 across condenser C-1 not every note will be lowered to exactly the same amount, the intervals will be made a little smaller or closer, sufficiently so as to be disagreeable to the musically trained ear. This can now be easily compensated for by reducing the series impedance which has the contrary effect of making the intervals wider. Thus, by arranging a double-pole switch S-1 and S-2 which when connecting condensers C-2 across condenser C-1 at the same time shorts the impedance I, and by adjusting condenser C-2 and impedance I, it is possible to have the transposing feature, without the disadvantage of a change in the intervals.

A further application of the series impedance is a simplified and improved method for producing small periodic variations of the pitch of the musical sounds produced, called the "tremolo-effect" so that the same means can be also used for another purpose, in other words, for periodically interrupting the main circuit and thereby producing an imitation of the plucked string, referred to herein as the "banjo-effect".

In Fig. 3 an embodiment of this circuit arrangement is depicted. Batteries B, glow lamp G, condenser C, resistors R-1 to R-n, keys K-1 to K-n; contacts Q-1 to Q-n are arranged in exactly the same way as in Fig. 2 and their connections do not require any further explanation. Reference character A designates a control lever pivoted at pivot E which can be moved a little to the right and to the left and which is capable of closing one of the contacts D-1 or D-2. Switch S is capable of connecting contact D-2 to one end of the impedance I when in the lower position, or connecting contact D-1 to contact D-2 when in the higher position. First the case when switch S is closing contact D-2 as indicated in Fig. 3 is considered. Suppose that control lever A is in the intermediary position not touching contacts D-1 or D-2, the main circuit, which is broken between the negative pole of the battery and the output transformer T-1, is completed through switch S, contact D-2 and through the impedance I. By moving contact lever A to the right and to the left impedance I will be short-circuited every time control lever A touches contact D-2, thus causing a small drop of pitch repeating periodically, (i. e. the desired tremolo effect). If switch S is put in the upper position, contacts D-1 and D-3 will be con-

5 nected to each other and the negative pole of the battery, while control lever A, as always, is connected to the upper end of the primary winding of the output transformer T-1. Thus 10 the main circuit is completely interrupted unless control lever A is moved to the right and to the left and intermittently closes contacts D-1 or D-2. This means that operating one of the keys K-1 to K-n alone is not sufficient 15 to produce the note because it is necessary to also operate the control lever A simultaneously. Every time when contact D-1 or D-2 is closed the oscillations will be started, so that instead of a continuous note a sound starting and stopping several times a second will be obtained 20 which simulates the effect of a banjo or mandolin. By giving to the control lever A freedom in another direction as, for instance, vertically to the plane of the drawing, the operator can utilize this motion preferably for varying the volume.

25 The value of impedance I is not at all critical, but depends slightly on the total impedance in the circuit. A resistance of about 1500 to about 3000 ohms is satisfactory in most cases.

30 From the preceding consideration, the importance of the influence of series impedances on the tuning of electrical musical instruments becomes apparent. Evidently even the primary 35 of the output transformer, usually arranged in the main circuit, has a certain impedance, which is also varying for instance due to direct current magnetization of the iron core or due to the reflection of the load on the secondary 40 winding back to the primary. Of course, these variations of impedance in the main circuit are undesirable. A simple method to reduce them to a negligible amount is to connect another transformer T-2 after T-1, so that secondary Se-1 of T-1 is connected through the 45 volume control potentiometer V to the primary Pr-1 of T-2 and only the secondary Se-2 of transformer T-2 is connected to the thermionic amplifier M and sound producing means 50 L. The impedances of Se-1 and Pr-2 are preferably matched with each other and with that of volume control V, and the winding ratio of transformers T-1 and T-2 is chosen so as to give a combined turn ratio 55 advantageous for the amplification.

55 The manifold and important advantages of this arrangement are obvious. The coupling between the main circuit of the glow-discharge lamp oscillator and the amplifier becomes extremely loose. Feed-backs, changes of impedance in the main circuit, direct current magnetization of the transformer core are eliminated. The volume control is dealing with a pure A. C. current without any D. C. component, 60 so that the load on it is considerably reduced thus eliminating scratches, cracking noises etc. in the sound-producing means when adjusting the volume of the sound.

65 Electrical musical instruments of the present type which are capable of producing numerous musical notes of different respective pitches and which essentially consist of a glow-discharge lamp, a condenser, a current source and a sound-producing means in series with said glow-discharge lamp, a plurality of resistors in series 70 capable of being shunted partly or totally across the condenser, function as satisfactorily from the electrical point of view as from the musical point of view. The instruments can be 75 built at little cost, only take up small space

and can be operated for a long time without any replacements whatever.

Since the frequency of the glow-discharge lamp oscillator varies not only with the resistance in circuit, but with the capacity and 5 electro-motive force as well, electrical musical instruments of the glow-discharge lamp type can be built in which a plurality of musical notes of different respective pitches are produced by varying the electro-motive force or 10 the capacity in the circuit.

15 Instruments in which the different musical notes are obtained by different voltages tapped off on one or on a plurality of current sources or potentiometers have been already described, and apart from the slight inconvenience of the relatively higher voltages involved, are practicable especially when the operating current is obtained from the electric supply lines of a 20 public utility.

25 The capacity method of tuning, however, is much simpler and more reliable in operation, and the circuit is practically identical with that of resistance tuning which can be easily seen, for instance, from Fig. 2. It is only necessary to put two resistors of adequate value in the place of condensers C-1 and C-2 and substitute a plurality of condensers for resistors R-1 to R-n and the circuit will be capable of producing musical oscillations. Now condensers 30 have the advantage of being readily obtainable on the market in the desired capacity values and their capacity can be easily varied by compression, etc. for tuning purposes. In addition to the foregoing condensers they are relatively 35 small and inexpensive.

40 The two fundamental circuits for a glow-discharge lamp musical instrument with condenser tuning may be seen in Figs. 4 and 5. In Fig. 4 a series arrangement of condensers is 45 illustrated whereas in Fig. 5 a parallel arrangement is depicted. Both circuits depict only one glow-discharge lamp but obviously a plurality of lamps in similar arrangements can be also used, since the circuits are equally adaptable 50 for monophonic (solo) and polyphonic (chord) instruments. Of course, a great variety of other circuits with condensers are possible, all of which can be of advantage for special purposes. In fact in most of the glow-discharge lamp 55 circuits resistances and condensers can be used interchangeably without interfering with the ability of the circuit to produce electrical oscillations. The values of resistors and condensers, of course, might have to be changed. The two 60 circuits to be described, however, have some special advantages, which distinguish them from the great variety of possible combinations.

65 Referring to Fig. 4, the fundamental circuit of an electrical musical instrument is shown but parts for controlling tone quality, volume, pitch etc. are omitted for sake of clarity. In a main circuit are the glow-discharge lamp G, current source B, sound-producing means L and resistance R, all in series. This circuit is closed 65 and the lamp is lighted. In an auxiliary circuit, a plurality of variable condensers C-1 to C-n are arranged in series with each other and switching keys K-1 to K-n with contacts Q-1 to Q-n are normally open. A switching 70 key and contact is provided for each condenser. When any of the switching keys is operated, a number of condensers in series up to the particular key will be shunted across the resistance R, so that the conditions for producing oscil- 75

lations are established. The condensers, switching-keys and contacts are arranged so as to shunt the resultant capacity up to the key operated across the resistance R . The same effect can be obtained by shunting the resultant capacity across the glow discharge lamp which might change the wave-form or amplitude of the oscillations produced, but this does not affect the frequency at all.

10 The variable condensers $C-1$ to $C-n$ are preferably adjusted so that the instrument will play a different note of the tempered scale for every switching-key operated. From the law governing the resultant capacity of condensers in series, it follows that the resultant capacity is always smaller than the capacity of any of the single condensers. In the case of two condensers in series, it is always the smaller which has more influence to the resultant capacity. A 15 simple calculation shows that it is desired to produce successive notes of the tempered scale in the right order by operating keys $K-1$ to $K-n$ of the circuit shown in Fig. 4, condenser $C-2$ will be considerably larger than condenser $C-1$, and condenser $C-3$ will be smaller than condenser $C-2$ and condenser $C-4$ smaller than condenser $C-3$, etc. The actual values for condensers $C-1$ to $C-n$ can be easily found by 20 considering the fact that the frequency of oscillations is approximately in inverse ratio with the capacity and resistance in the circuit and from the condenser equation determining the resultant capacity of two condensers in series.

Referring to Fig. 5, a parallel arrangement of 25 variable condensers is depicted and the rest of the circuit is identical with Fig. 4. The fundamental difference between the circuits of Figs. 4 and 5 is that in the latter the switching keys $K-1$ to $K-n$ and the contacts $Q-1$ to $Q-n$ are normally closed, so that all the condensers $C-1$ to $C-n$ are connected in parallel and across the resistance R . Consequently, continuous oscillations are set up in the main circuit consisting of current source B , sound-producing 30 means L , glow-discharge lamp G and resistance R . The last condenser $C-n$, however, has preferably a very high capacity and is many hundred times larger than any of the preceding condensers. For instance, a capacity of 4 to 10 microfarads may be used so that the frequency 35 of the continuous oscillation will be extremely low and will be of the order of only one oscillation in several minutes, and thus inaudible. As soon, however, as any of the switching-keys is 40 depressed, one of the contacts $Q-1$ to $Q-n$ will be interrupted, the condensers beyond the particular key disconnected and only the condensers before the key remain in the circuit and produce an oscillation of musical frequency. 45 For instance, if the switching-key operated is $K-2$, then $C-3$, $C-4$ . . . $C-n$ (this latter being the large "silencing condenser") will be disconnected and only $C-1$ plus $C-2$ left in the circuit.

50 As it will be readily seen, the fundamental difference between the circuits in Fig. 4 and Fig. 5 is that in the former in case several keys are operated simultaneously, the note corresponding to the lowest pitch key will sound, while in the latter the note corresponding to the highest. Both possibilities have certain advantages for special purposes and embody the very important feature, that whatever keys are operated simultaneously no irrational notes will be heard, 55 meaning by irrational a note which is falling

between two successive notes of the tempered scale.

It is possible to combine the two circuits in Fig. 4 and Fig. 5 in one instrument with a single keyboard. An instrument of this kind comprises 5 two glow-discharge lamps, a resistance in series with each lamp and a set of condensers in parallel respectively in series with their corresponding breaking or closing contacts associated to these resistors. Every key of the common keyboard operates two contacts independent from each other, one contact is opened and another closed simultaneously when the key is depressed. Of course, current source and sound-producing means can be in common for both 1 glow-discharge lamp circuits.

An instrument of the present type has the advantage that it can play any two notes of its range simultaneously, since it actually consists of two independent instruments, one of which 2 always plays the highest and the other always 2 the lowest note for any two keys depressed.

I claim:—

1. An electrical musical instrument comprising an electrical circuit containing a source of current, a condenser with a shunt resistance, a glow-discharge lamp, sound producing means capable of emitting sounds, and a variable impedance all in series, means for varying said impedance whereby the pitch of the sound emitted by said sound producing means is raised when said impedance is increased and the pitch of the said sound is lowered when the said impedance is decreased.

2. An electrical musical instrument comprising a circuit containing a source of current, a condenser with a shunt resistance, a glow-discharge lamp, a transformer having a primary in said circuit, and an impedance, all in series, means for short-circuiting said impedance and a sound-producing means operatively associated with the secondary of said transformer, said sound producing means being capable of emitting a sound, the pitch of said sound being raised when the said impedance is in circuit, and the pitch of said sound being lowered when said impedance is short-circuited.

3. An electrical musical instrument comprising a main electrical circuit containing a source of current, a glow-discharge lamp, a condenser, a transformer having a primary in said circuit, and an impedance all in series; an auxiliary circuit containing a plurality of resistances in series; a switching key for each of the said resistances located between each common point of two adjoining resistances and one side of the condenser, said key being normally open to disconnect the resistance from the main circuit and being capable of actuation for shunting a selected plurality of said resistances across said condenser thereby completing the main circuit and causing current to flow through said lamp; means for short-circuiting said impedance and sound producing means operatively associated with the secondary winding of the aforesaid transformer and capable of emitting sound, the pitch of the emitted sound being the highest when one resistance is operative and the lowest when all of the series resistances are operative and intermediate when a plurality of resistances are operative; the musical intervals between all the notes produced being capable of simultaneous variation when said impedance in the main circuit is a short-circuited.

4. An electrical musical instrument comprising

- ing a main electrical circuit containing a source of current, a glow-discharge lamp, a condenser, a transformer having its primary in said circuit, and an impedance all in series; an auxiliary circuit containing a plurality of resistances in series, a switching key for each of the said resistances located between each common point of any two adjoining resistances and one side of the condenser, said key being normally open 5 to disconnect the resistance from the main circuit and being capable of actuation for shunting a selected plurality of said resistances across said condenser and causing current to flow through said lamp; and sound producing means 10 operatively associated with the secondary of said transformer and being capable of emitting sound of different pitch for every switching key operated; a second auxiliary circuit containing a condenser variable in steps and a double-pole 15 switch capable of shunting said condenser across the main circuit condenser and simultaneously short-circuiting the main circuit impedance thereby lowering the pitch of every note the instrument is capable of producing by a definite 20 amount and compensating for differences in the aforesaid change for the different notes and thereby keeping the musical intervals between the notes substantially constant by means of the aforesaid double action.
- 30 5. An electrical musical instrument comprising an electrical circuit containing a source of current, a condenser with a shunt resistance, a glow-discharge lamp, a sound producing means capable of emitting sounds, and an impedance all in series, means for short-circuiting said impedance including, an electrical contact connected across said impedance capable of being opened and closed in rapid succession the pitch of sound emitted by said sound producing means 35 being raised when said contact is opened and the pitch of said sound being lowered when said contact is closed and short-circuits the said impedance.
- 40 6. An electrical musical instrument comprising a main electrical circuit containing a source of current, a glow-discharge lamp, a condenser, a sound producing means and an impedance all in series; an auxiliary circuit containing a plurality of resistances in series, a switching key 45 for each of the said resistances located between each common point of any two adjoining resistances and one side of the condenser, said key being normally open to disconnect the resistance from the main circuit and being capable 50 of actuation for shunting a plurality of said resistances across said condenser and causing current to flow through said lamp; and an electrical contact capable of rapidly opening and closing a short circuiting lead connected across 55 said impedance in the main circuit; said sound producing means being capable of emitting sound of different pitch for every switching key operated, the pitch of said sound being raised when said contact is opened and the pitch of 60 said sound being lowered when said contact is closed and short-circuits said impedance.
- 65 7. An electrical musical instrument comprising a main electrical circuit containing a source of current, a condenser with a shunt resistance, a glow-discharge lamp, a sound producing means 70
- capable of emitting sound, and an electrical contact all in series, a switch capable of connecting an impedance across said contact and disconnecting it therefrom; said sound producing means emitting a musical sound the pitch of 5 which varies when said contact is rapidly opened and closed and the impedance is connected across the contact, said musical sound being started and stopped when said contact is operated and the impedance is disconnected 10 therefrom.
8. An electrical musical instrument comprising a main electrical circuit containing a source of current, a glow-discharge lamp, a condenser and the primary of a transformer all in series; 15 an auxiliary circuit containing a plurality of resistances in series, a switching key for each of these resistances located between each common point of two adjoining resistances and one side of the condenser, said key being normally 20 open to disconnect the resistance from the main circuit and being capable of actuation for shunting a plurality of said resistances across said condenser and for causing current to flow through said lamp; an electrical contact inserted in said main circuit capable of rapidly 25 opening and closing same, a switch capable of connecting an impedance across said contact and disconnecting it therefrom, and sound producing means operatively associated with said 30 transformer and being capable of emitting sound of different pitch for every switching key operated; the pitch of the emitted sound varying when said main circuit contact breaker is operated and when the impedance connected across 35 the same is alternatively short-circuited, the said sound starting and stopping in rapid succession when said contact is operated and the impedance is disconnected therefrom.
9. In an electrical musical instrument, the 40 combination comprising a glow-discharge lamp adapted to produce electrical oscillations, a sound producing means adapted to produce sounds in accordance with said oscillations, manually operative elements for controlling the 45 frequency of said oscillations, and a variable impedance in series with said glow-discharge lamp, the pitch of sounds produced in said sound producing means by actuation of said manually 50 operative elements being collectively raised 55 when said impedance is increased and said pitches being collectively lowered when said impedance is decreased.
10. In an electrical musical instrument, the 60 combination comprising a glow-discharge lamp circuit adapted to produce electrical oscillations, a sound producing means associated with said circuit adapted to produce musical sounds in accordance with said oscillations, manually operative elements for controlling the frequency 65 of said oscillations and to produce musical sounds having definite intervals, a shunt condenser for collectively varying the pitch of said sounds by approximately the same amount, and an adjustable impedance in series with said 70 glow-discharge lamp for correcting the effect of said condenser and to maintain said intervals constant.
